UNITED STATES PATENT OFFICE.

C. F. THEODOR STEINWAY, OF NEW YORK, N. Y.

KEY-FRAME BED FOR PIANO-FORTES.

SPECIFICATION forming part of Letters Patent No. 232,857, dated October 5, 1880.

Application filed May 13, 1880. (No model.)

To all whom it may concern:

Be it known that I, C. F. THEODOR STEINWAY, of the city and State of New York, have invented certain Improvements in Key-Board or Key-Frame Beds for Piano-Fortes, of which the following is a specification.

My improvements relate to the construction of the wooden bed which supports the key-frame in a piano-forte, and are designed to prevent the bed from acting as a sounding-board in augmenting the sound or thud made by the key-levers in striking against the touch-rail of the key-frame, and also to prevent the warping of the bed and consequent upheaval of any part of the key-frame; and my invention consists in a key-frame bed composed of parallel strips of wood and end cleats, in which the parallel strips are secured by tongued and grooved joints, the vertical joints between the parallel strips being filled with a soft packing, preferably of fibrous material, for the purpose of obstructing the lateral transmission of vibrations from one strip to another.

The accompanying drawings are as follows: Figure 1 is a top view of my key-frame bed. Fig. 2 is a side elevation of one of the strips, showing the cleats in section through the line *x x* on Fig. 1; and Fig. 3 is a transverse section through the line *y y* on Fig. 1. Fig. 4 is an isometrical perspective of a portion of the case of an upright piano-forte, showing a few of the keys, a part of the key-frame, and a portion of my improved key-frame bed fastened in the usual manner to the projecting arms of the case.

Referring to the drawings, it will be seen that the bed is composed of a number of narrow wooden strips, *A*, which are secured at their ends respectively to the cleats *B* by tongued and grooved joints *b b*. The strips *A* are also tongued and grooved to each other; but the opposed vertical planes of their tongued and grooved joints *a* are slightly separated, and are prevented from direct contact with each other by the interposition between them of the soft packing *C*, preferably of fibrous material.

In the drawings the fibrous packing *C* is represented as being interposed between the bottom of the groove of each strip and the face of the tongue of the adjoining strip.

The packing may be introduced into the joints *a* either above or below the tongues; or, if desired, between all the opposed vertical faces of the joint, the effect of such interposition being that vibrations set up in one of the strips are not readily communicated to the adjoining strip.

It will, of course, be understood that the packing may be composed of any material incapable of acquiring and transmitting sonorous vibrations.

The key-board beds heretofore employed are of such width that they are liable, by their warping, to cause an upheaval of a portion of the key-frame and a consequent derangement of the action.

By the use of the narrow strips *A* all danger of warping is avoided, and the strips themselves, by reason of their small area in cross-section, are capable of being more easily and effectually seasoned than the wider stuff heretofore used for the panels of beds.

My improved key-frame bed, which may be applied with equal advantage to both horizontal and upright pianos, is secured to the case of the piano in the same way that the ordinary key-board bed is secured.

In an upright piano-forte, as shown in Fig. 4, the end cleats, *B B*, are respectively fastened to the under sides of the arms *D*, projecting from the front of the case *E*.

The keys *F* are arranged upon the usual key-frame *G*.

In Fig. 4 of the drawings a portion of the key-frame is broken away to more clearly exhibit my improved key-frame bed and its relation to the keys.

When the key is depressed the front end, *f*, of the key-lever strikes against the usual cushion upon the touch-rail *g*, and makes a noise which, when the ordinary key-board bed is employed, is like the sound of a drum, this noise being made more perceptible because the ordinary key-frame bed or key-board acts as a sounding-board and unpleasantly augments it. By my invention this unpleasant augmentation of the noise of the key is prevented.

I claim as my invention—

1. The combination, in a piano-forte, of the keys and key-frame with a key-frame bed com-

posed of narrow longitudinal strips secured at their ends respectively to transverse cleats, substantially as described.

2. In a key-frame bed composed of parallel wooden strips, packing of fibrous or other soft material interposed between the adjoining edges of the strips, substantially as and for the purpose set forth.

3. In a piano-forte, a key-frame bed composed of the parallel wooden strips A, secured

at their ends respectively to the cleats B B, and tongued and grooved to each other, and having interposed between their adjoining edges the packing C, substantially as and for the purposes described.

C. F. THEODOR STEINWAY.
